(57) **CLAIM**

The ornamental design for a airplane wing attachment, as shown and described.

DESCRIPTION

FIG. 1 is a front elevational view of the airplane wing attachment of the present invention;

FIG. 2 is a rear elevational view of the airplane wing attachment of FIG. 1;

FIG. 3 is a left elevational view of the airplate wing attachment of FIG. 1;

FIG. 4 is a right side elevational view of the airplane wing attachment of FIG. 1;

FIG. 5 is a top plan view of the airplane wing attachment of FIG. 1;

FIG. 6 is a bottom plan view of the airplane wing attachment of FIG. 1; and,

FIG. 7 is a top, rear, right side perspective view of the airplane wing attachment of FIG. 1.

The broken lines showing of an air plane wing and cords in FIG. 7 are for illustrative purposes only and form no part of the claimed design.
